GAS-LIFT PUMP

Wilbur J. Crites, Bartlesville, Okla., assignor to
 Phillips Petroleum Company, a corporation of
 Delaware

Application June 1, 1936, Serial No. 82,974

11 Claims. (Cl. 103—234)

This invention relates broadly to maintaining reservoir volume or bottom hole pressure in wells.

More particularly, the invention relates to methods and devices for returning gas to producing formations while raising liquid from well holes.

In wells such as oil wells, the rate of flow from the producing formations is dependent, among other things, upon the so-called bottom hole pressure which in turn is dependent, in any given formation, upon the amount of gas present in the producing reservoir available for forcing the oil or other liquid therein through the pores or interstices of the formation into the well hole, as will be well understood by one skilled in the art.

In some wells, the bottom hole pressure is sufficient to force the liquid produced to the surface without the aid of extraneous measures such as gas-lift, pumps, and the like, until the bottom hole pressure is reduced to such a point that the fluid column in the well balances the bottom hole pressure, in which case natural flow will cease, or so nearly balances this pressure that the rate of flow is no longer economically sufficient. In other wells, the bottom hole pressure is never sufficient to produce the well without resort to extraneous measures.

As wells flow under these bottom hole pressures, a great deal of the gas within the formation reservoir is exhausted to the surface either in solution with the liquid or in the form of globules in the liquid column. In either case, the amount of gas contained in the reservoir and useful for raising the oil or other liquid is lessened with a consequent reduction in bottom hole pressure. Furthermore, as liquid is removed from the formation reservoir, the gas in the reservoir may expand into the space vacated by the liquid thus further lowering the bottom hole pressure.

After bottom hole pressures are so reduced that the well will no longer produce as a flowing well, resort must be had to some additional means to raise the liquid from the well hole. In some instances it is economically desirable to employ the gas-lift method of flowing the well in which gas under pressure is introduced through a conduit from the well surface to liquid column to aerate or lighten the same, thus enabling the lowered bottom hole pressures to flow the well. Either in place of the gas-lift, or after the gas-lift is no longer effective, some type of pumping device must be employed for further production. Electrically driven centrifugal pumps, gas-lift pumps and the so-called sucker rod pumps are

among those used depending upon the conditions encountered in the particular well or field or the rate of production possible from the well.

In any case, it has been found desirable in many fields to retain as much gas in the producing formation as possible thereby to maintain the bottom hole pressure or reservoir volume thus favoring the ultimate recovery from the formation of a greater quantity of oil or other liquid. It, therefore, has become the practice in some pools, notably the Van Texas, to introduce gas into the formation as the oil or other liquid is removed, thereby to repressurize the same, maintain bottom hole pressure and reservoir volume. By this practice in combination with controlled flow, it has been found in many instances that a greater ultimate recovery is possible and orderly encroachment of water is assured, as is well understood by those skilled in the art.

There are, however, many fields which are now on their way to depletion which have not been produced in conformity with this principle and in which it is desirable to return gas to the formation either to increase the bottom hole pressure or to maintain those already existing. In general, it is believed to be desirable to increase the amount of gas returned to the formation or reservoir as the depletion progresses.

The primary object of the present invention is to return gas to the producing formation or reservoir.

An additional object of the invention is the provision of a device which will accomplish the first named object and which will also operate as a gas-lift pump for raising liquid to the well surface.

Still another object of the invention is to return gas to the producing formation in volumes equal to or greater than that of the liquid removed.

Other objects of the invention are the conservation of reservoir gas volumes, the production of liquid from a well with a minimum gas-liquid ratio and the provision of a device for accomplishing the aforementioned objects which will be simple in operation, contain a minimum of moving parts and be capable of easy installation.

Further objects of the invention will be apparent from a consideration of the detailed specification, claims and the drawing in which:

Figure 1 is a longitudinal view, partly in section, of an embodiment of applicant's invention in place in a well.

Figure 2 is a detailed enlarged sectional view of the pumping element and valve mechanism.

Referring particularly to Figure 1, a well hole is indicated at 10 the bottom portion 11 of which is adapted to receive oil or other liquid forced from the producing formation 11'. The usual casing 12 extends within the well hole and is generally cemented in place at the edge of the producing strata as indicated at 13 as will be understood by those skilled in the well drilling art. A string of tubing 14 is arranged within the casing 12 and extends to the well surface where it passes through the casing head 15. At the upper end of the tubing string 14, a choke 16 is mounted to control the flow of fluid through the tubing string 14 as the well is produced. The choke shown is similar to the one described in Knowlton and Crites Patent 1,905,592, although other well known flow heads or chokes may be employed. A length of tubing 17 of larger diameter than the tubing 14 is attached thereto at the lower end thereof to form a chamber 18 in which is mounted a partition 19 dividing the chamber 18 into two parts, the lower of which serves as a liquid accumulation chamber as indicated at 18'. A packer 21 forms a seal between the casing 12 and tubing 17 to seal off the bottom portion of the well hole. The tubing string 14 is offset adjacent the lower end thereof as at 22 and extends through the partition 19 and into the chamber 18' to a point near the bottom thereof, and carries at its lower end a standing valve 23 in a valve cage 24 which acts as a check valve to prevent the return of fluid from the eductor tubing 14 to the chamber 18'. The tubing 17 likewise is provided with a standing valve 25 in a valve cage 26 which serves to admit liquid from the well hole to the liquid accumulation chamber 18' while preventing the return of liquid therefrom.

A pumping element indicated generally at 27 is mounted in the partition 19 and extends therethrough with a portion thereof in the accumulation chamber 18' and a portion above the partition exposed to gas under pressure which may be introduced through the pipe 28 to the casing 12 and thence through the ports 29 to the upper portion of the chamber 18.

Referring to the pumping element 27 in detail, as shown in Figure 2, a housing indicated at 29 is secured in an aperture in the partition 19 as by wells 30 or any other conventional means. The casing 29 may be constructed in two parts, an upper portion 31 and a lower portion 32. The upper portion 31 is provided with a chamber 33 in which is mounted a bellows 35 exposed to the high pressure gas in the upper portion of the chamber 18 by means of the port 34. Depending from the bellows 35 and fixed thereto is a valve stem 36 having mounted thereon, to move therewith, valve heads 37 and 38 adapted to seat on valve seats 39 and 40, respectively, formed in the upper portion 31 of the housing 29. The valve head 37 may be fixedly or adjustably secured to the stem 36 in any well known manner while the valve head 38 is preferably secured to the stem as by a nut 41 mounted on the stem as by screwthreads 42. The lower portion 32 of the housing 29 is connected to the upper portion 31 as by screwthreads 43, and serves as a spring guide and housing for a compression spring 44 which surrounds the stem 36 and is mounted between a flange 45 in the lower housing portion 32, and a plate 46 mounted on the stem 36 as by a screw nut 47. The spring

44 acts as in opposition to the bellows 35 normally to maintain the valve head 37 seated on its seat 39, and may have its tension varied by the nut 41 thereby to vary the force required to operate the bellows 35.

Bores 48 and 48' extend partially through the partition 19 in a radial direction and communicate with a port 50 formed in the tubing 14 and a port 49 formed in the tubing 17. A relief passage 51 is formed in a side wall of the upper portion 31 of the housing 29 and places the low pressure side of the bellows 35 in communication with the bore 48' and thence to the exterior of the tubing 17 through the port 49 to relieve any back pressure which would tend to build up behind the bellows 35 in operation. A bore or passage 51' is formed in the housing part 31 and communicates with the passage 48' and a port 52 formed in the valve seat 40. With the valve heads in the positions shown, it will be apparent that any gas in the chamber 18' may flow through the port 52, passage 51', passage 48' and port 49 to the exterior of the tubing 17. A second chamber 53 is formed in the upper portion 31 of the housing 29 in which is mounted a bellows 54 having one side exposed to the pressure existing in the bellows chamber 33 through the medium of the port 55 and the other side exposed to the pressure existing in the chamber 18' through the medium of the port 56. A plug 57 may be screwed into one end of the chamber 53 and is provided with a passage 58 extending from the chamber 53 to a passage 59 in the housing portion 31 which in turn communicates with the eduction tubing 14 through the passage 48' and port 50. A needle valve 60 is secured to one side of the bellows 54 and serves to open and close the bore 58 in response to pressure differentials existing at one side or the other of the bellows. Gas under pressure may pass from the bellows chamber 33 into the spring housing 32 when the valve head 37 is open and the valve head 38 in closed position, through the ports 51 in the valve head 38 and the ports 62 in the spring follower plate 46. Ports or openings 63 in the spring housing 32 provide for gas passage therefrom into the liquid accumulation chamber 18'.

The pumping device is assembled on the tubing string 14 at the well surface. It is to be understood that the partition 19 together with the pumping element 27 is first welded or otherwise secured in place in the tubing 17 which is then slipped over the tubing string 14 and the upper end may be peened over into engagement with the tubing string and welded or otherwise secured thereto. The tubing string 14 together with the pumping device is then lowered within the well hole in the usual manner until the packer 21 seats against a shoulder (not shown) on the casing 12. The casing head is then sealed in any of the known ways as will be well understood by those skilled in the art. At this point, the lower end of the tubing 17 including the pumping element 27 will be submerged in the well fluid which will stand in the well hole at various heights depending upon the bottom hole pressure and available liquid.

In operation, the liquid standing in the well hole forces the standing valve 25 to rise thereby admitting liquid to the liquid accumulation chamber where it will seek its level. It is generally desirable to so proportion the chamber 18' that it will be entirely filled with liquid, although the device will operate satisfactorily with

partial filling. Air in the chamber 18' escapes therefrom through the ports 63, 62, 52, passage 48' and port 49 to the exterior of the tubing 17. Gas under pressure is then admitted through the pipe 28 to the casing 12 from whence it passes the ports 28 into the chamber 18 through the port 34 to the bellows chamber 33 where it exerts sufficient pressure upon the bellows 54 to compress the same, thus opening the valve 37 and closing the valve 38. It can now pass through the ports 61, spring ports 62 and ports 63 to the liquid accumulation chamber 18' wherein it exerts a pressure upon the surface of the liquid therein greater than the pressure exerted by the liquid in the well hole, thus forcing a slug of liquid into the eductor tubing 14 through the standing valve 23. At the same time the ports 55 and 56 are each exposed to equal gas pressures and the inherent spring of the bellows 54 maintains the needle valve 60 in closed position. When the liquid accumulation chamber has been exhausted of liquid the pressure of the admitted gas is reduced, generally by an intermitting valve at the well surface which shuts off the supply of gas at predetermined intervals, or any other form of control may be used, sufficiently to enable the spring 44 to close the valve 37 and open the valve 38. It is to be understood that the pressure differential necessary to operate the valve may be relatively small depending upon the setting of the spring tension. For instance, in some wells it may be necessary or desirable to use a gas pressure of around three or four hundred pounds per square inch to raise the liquid in which case the valve might be set to operate at a fifty-pound per square inch differential. As the valve 37 closes, the gas under pressure in the chamber 33 is cut off from the accumulation chamber 18' and the compressed gas within this chamber may escape through the ports 63, 61, 52 passages 51 and 48' and port 49 to the exterior of the tubing 17. At this instant, pressure on the side of the bellows exposed to the liquid accumulation chamber through the port 56 of the bellows 54, is reduced to a relatively low value whereas the pressure on the other side in communication with the bellows chamber 33 through the port 55 is maintained at a relatively high value, thus compressing the bellows 54, unseating the valve 60 and permitting gas under pressure to pass through the port 55, chamber 53 passages 58, 59 and 48 and port 50 to the eduction tubing 14 where it serves to aerate the column and to provide a compressible medium to aid in controlling the pressure in the accumulation chamber 18' in accordance with the setting of the choke 16. As the gas is exhausted from the liquid accumulation chamber, liquid from the well again enters the chamber through the standing valve to fill the same. The fluid in the eduction pipe is prevented from returning to the chamber by the standing valve 23. The intermitter or other control at the well surface then raises the gas pressure in the upper portion of the chamber 18 sufficiently to again open the valve 37 to repeat the cycle. It will then be apparent that after the eduction tubing has filled each slug of liquid passing thereunto forces a slug out at the top and the introduction of gas into the tubing during the gas exhaust of the chamber 18' serves to maintain the liquid in the eduction tube in a state of constant motion.

It will be observed that the packer 21 forms a sealed space between the tubing 17 and the well hole adjacent the producing formation.

Therefore, gas exhausted into this space cannot flow to the well surface but is returned to the producing formation or reservoir as indicated by the arrows 65.

It will now be apparent that an equal or greater volume of gas is returned to the formation than the volume of oil or liquid taken therefrom depending upon the gas pressure within the chamber 18', thus resulting in a re-pressuring of the reservoir, or as it may be expressed, maintenance of reservoir volume.

It is generally desirable to so locate the port 49 that the gas will be returned to that portion of the formation nearest to the space which it normally occupies in the producing reservoir.

While that aspect of the invention concerned with returning of gas to the formation is applicable to formations of most any type, it is particularly effective in those formations in which the producing sand is thick and in sections.

It is to be understood that the embodiment of applicant's invention illustrated in the drawing and described above is for the purpose of illustration only, and that changes in structure and design are contemplated within the scope of the subjoined claims.

I claim as my invention:

1. In a device for raising liquids from a well and for returning gas to a producing formation, a chamber for the accumulation of liquid located adjacent the producing formation, means to seal the chamber in the well bottom to form a closed space surrounding the chamber, a conduit for conducting gas under pressure to said chamber, a conduit for the eduction of liquid from said chamber, and means for exhausting the gas within the chamber to the closed space and to the formation.

2. In a gas-lift pumping device, a chamber in the well hole adjacent the producing formation, valve means within said chamber for the admission of liquid from said well to said chamber, means to form a sealed space between the chamber and the producing formation, means for conducting gas under pressure to said chamber, means for conducting liquid therefrom and means in communication with said chamber and said sealed space to conduct exhaust gas from said chamber to the formation.

3. In a device for raising liquids from a well and for re-pressuring producing formations, a casing extending within the well to a point adjacent said formation, a tubing within the well hole extending into the producing formation and spaced therefrom to form a chamber for the accumulation of liquid therein, a tubing string extending from the well surface to said chamber for the eduction of liquid therefrom, a source of gas under pressure in communication with said chamber, a packer between the casing and chamber to seal the space between the chamber and formation, and means to conduct the exhaust gases from said chamber to said sealed space.

4. In a device for raising liquid from a well reservoir, a liquid accumulation chamber within the reservoir, a packer between the well wall and said chamber forming a seal therebetween above said reservoir, a conduit for the induction of gas under pressure to said chamber, a conduit for conduction of liquid from said chamber to the well surface, a conduit for the exhaust of gas from said chamber to said reservoir, and means to control the flow of gas through said conduits.

5. In a device for raising liquid from a well reservoir and for returning gas thereto, a liquid

5 accumulation chamber in said reservoir, including a check valve to admit liquid to said chamber, a packer between said chamber and the well wall forming a seal therebetween, a gas induction conduit in communication with said chamber, a liquid eduction conduit extending into said chamber, a gas exhaust conduit extending from said chamber to said reservoir below said packer, and means responsive to pressure differences to 10 control the flow of gas through said induction and exhaust conduits.

6. In a device for raising liquids from a well and for re-pressuring the producing formation, a chamber within the well and extending into said 15 formation, a check valve for admitting liquid to said chamber, a seal between said chamber and said formation adjacent the upper end of said chamber, means for introducing gas under pressure to said chamber, means for conducting liquid 20 therefrom to the well surface, and means for conducting exhaust gas from said chamber to said formation.

7. A device for raising liquids from a well and for returning gas to the producing formation, comprising a liquid accumulation chamber within said well extending into said formation, means for sealing said chamber in said formation, a conduit in communication with said chamber for the introduction of gas under pressure thereto, a 25 conduit in communication with said chamber for the eduction of liquid therefrom, a conduit for exhausting gas from said chamber to the producing formation, and means to control the flow of liquid through said eduction conduit 30 thereby to control the volume of gas to be exhausted to said formation.

8. In a device of the character described, a chamber for the accumulation of liquid therein, a conduit for admitting gas under pressure to 40 said chamber, a conduit for the eduction of liquid from said chamber, a passage from said chamber to the exterior thereof for the exhaust of gas therefrom, a conduit for the introduction of gas into said liquid eduction conduit, means 45 to control the admission of gas to said chamber and the exhaust of gas therefrom, and means responsive to pressure differences between the gas admission conduit and said chamber to control the admission of gas to said last named conduit.

50 9. A gas operated pump structure for raising liquids from a well hole and for returning gas to a producing formation, comprising a pump housing adjacent the producing formation having a partition dividing the housing into upper and lower chambers, a packer between the housing and producing formation to seal the space between the housing and formation, inlet ports to admit the gas under pressure to the upper chamber, a check valve adjacent the bottom end of the 55 lower chamber for the admission of liquid thereto, a liquid eduction conduit mounted in the partition having its lower end in communication

with the lower chamber, and valve means mounted in the partition directing the gas under pressure into the lower chamber to force the liquid accumulated therein into the induction tube and an exhaust port in the valve for exhausting the 5 gas in the lower chamber into the formation for repressuring purposes when the source of gas supply is closed at the surface of the well.

10. A gas operated pump structure for raising liquid from a well hole and for returning gas to 10 a producing formation, comprising a pump housing adjacent the producing formation having a partition dividing the housing into an upper gas chamber and a lower liquid accumulation chamber, a packer between the housing and producing formation to seal the space between the housing and formation, a check valve in the lower chamber, a liquid eduction pipe mounted in the partition having its lower end in communication with the lower chamber and connecting with the well tubing at its upper end, a pilot valve mechanism mounted in the partition with a tension spring to keep the valve normally seated, a bellows connected to the valve and subjected to the gas pressure to lift the pilot valve from its seat 15 thus directing the gas pressure into the accumulation chamber to force the oil therein into the eduction pipe and a by-pass for exhausting the accumulation chamber of gas when the gas pressure is closed at the surface of the well and to 20 direct the gas pressure into the gas formation and thus repressurize the same.

11. A gas operated pump structure for raising liquid from a well hole and for returning gas to a producing formation, comprising a pump 35 housing adjacent the producing formation having a partition dividing the housing into an upper gas chamber and a lower liquid accumulation chamber, a packer between the housing and producing formation to seal the space between the 40 housing and formation, a liquid eduction pipe mounted in the partition having its lower end in communication with the lower chamber and connecting with the well tubing at its upper end, a pilot valve mechanism mounted in the partition 45 with a tension spring to keep the valve normally seated, a bellows connected to the valve and subjected to the gas pressure to lift the pilot valve from its seat against the pressure exerted by the tension spring to thus allow the pressure gas to 50 enter the accumulation chamber to force the liquid therefrom, a by-pass to exhaust the accumulation chamber when the gas pressure means is closed and adapted to direct the gas from the accumulation chamber into the liquid formation 55 to repressurize the same and a second by-pass controlled by a bellows adapted to establish communication between the gas pressure and the eduction pipe when the pilot valve is closed to aerate the oil column.
